J. BORDAS,
BLOW-OUT PATCH,
APPLICATION FILED JUNE 19, 1922,

Patented Aug. 8, 1922.

INVENTION

John Borod.

UNITED STATES PATENT OFFICE.

JOHN BORDAS, OF MIAMI, FLORIDA.

BLOW-OUT PATCH.

Specification of Letters Patent. Patented Aug. 8, 1922.

1,425,234.

Application filed June 19, 1922. Serial No. 569,539.

To all whom it may concern:

Be it known that I, JOHN BORDAS, a citizen of the United States, residing at Miami, in the county of Dade and State of Florida, have invented certain new and useful Improvements in Blow-Out Patches, of which the following is a specification.

This invention relates to blowout patches especially adapted for use on motor vehicle wheels.

An important object of this invention is to provide an emergency patch having simple means whereby the inner tube is fully protected, so that pinching of the inner tube is positively prevented.

A further object is to provide a blowout patch which may be readily and conveniently adjusted for use on tires of various sizes.

26 A further object is to provide a blowout patch which is of highly simplified construction, simple to apply and cheap to manufacture.

Other objects and advantages of the invention will be apparent during the course 25 of the following description.

In the accompanying drawing forming a part of this invention

Figure 1 is a perspective of the improved 30 blowout patch,

Figure 2 is a vertical transverse sectional view through the same,

Figure 3 is a group perspective illustrating the fastening means for the improved 35 blowout patch.

In the drawing wherein for the purpose of illustration is shown a preferred embodiment of the invention the numeral 5 designates a tire casing within which the improved blowout patch is adapted to be arranged. In applying the improved blowout patch the same is arranged within the casing inwardly of a hole so as to form a temporary means for repair. However, the improved blowout patch is somewhat long and is possessed of the strength to withstand continued use in the casing in the event of it being impossible to promptly replace the tire.

50 The improved blowout patch is generally designated by the numeral 6 and consists of a series of sheets of fabric or other material possessed of the necessary strength.

The layers of material which form the blowout patch gradually decreases in length toward the outer surface of the patch so that

the ends of the patch are tapered. This positively prevents pinching of the tube 10, and also renders the patch more pliable without detracting greatly from its strength. 60

Figure 1 illustrates that the body of the patch is curved longitudinally and transversely and is provided along one longitudinal edge with a plurality of latch plates 15 having spaced openings 16 adapted to receive 65 outwardly projecting aligned ears 18 of a strengthening and fastening plate 20. When the aligned ears 18 are extended through the openings 16 a locking rod 22 is passed through the ears so as to securely hold the 70 latch plate in position.

It will be observed that the latch plates 15 may by reason of the series of openings 16 be adjusted for use in connection with 75 tires of various sizes.

Attention is directed to Figure 2 where-in it is illustrated that the strip 20 is secured to one longitudinal edge portion of the body by means of fastening rivets 30 and the said fastening rivets are also 80 utilized to hold the tongue 31 in position.

The tongue is arranged within the body and extends over the longitudinal edge of the same so as to prevent the inner tube from 85 being pinched.

With reference to the foregoing description taken in connection with the accompanying drawing, it will be seen that the improved blowout patch may be applied to a tire without the possibility of pinching the 90 tube and without inconvenience on the part of the operator, all of which contributes to the desirability of the patch.

It is to be understood that the form of the invention herewith shown and described is to 95 be taken as a preferred example of the same and that such minor changes in arrangement and construction of parts may be made as will remain within the spirit of the invention and the scope of what is claimed.

Having thus described the invention what is claimed is:—

1. A blowout patch comprising a transversely curved body adapted to be arranged within a tire and consisting of a plurality of 105 layers of material, the ends of which terminate in spaced relation to each other whereby the body is gradually tapered toward its ends, latch plates extending laterally from one side of said body and having spaced 110 openings, and a strengthening strip secured to one longitudinal edge portion of said

body and having aligned ears adapted for movement through said openings whereby the latch plates are connected to said strip.

2. A blowout patch comprising a transversely curved body adapted to be arranged within a tire and consisting of a plurality of layers of material, the ends of which terminate in spaced relation to each other whereby the body is gradually tapered toward its ends, latch plates extending laterally from one side of said body and having spaced openings, a strengthening and attaching strip secured to one longitudinal edge portion of said body and having aligned ears adapted for movement through said openings whereby the latch plates are connected to said strip, and a locking rod extending through said ears and holding said latch plates in position.

3. A blowout patch comprising a transversely curved body adapted to be arranged

within a tire and consisting of a plurality of layers of material, the ends of which terminate in spaced relation to each other whereby the body is gradually tapered toward its ends, latch plates extending laterally from one side of said body and having spaced openings, a strengthening and attaching strip secured to one longitudinal edge portion of said body and having ears adapted for movement through said openings, a locking rod extending through said ears, a tongue arranged within said body, and fastening devices extending through said strip, the said body and the said tongue. 35

In testimony whereof, I have affixed my signature in the presence of two witnesses.

JOHN BORDAS.
